UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

MEANS FOR REINFORCING METALLIC PLATES.

Application filed September 3, 1926. Serial No. 133,435.

Reference is had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

10 My invention relates to means of reenforcing a metallic plate by forming integral corrugations, embossments or ribs therein and resides in the particular and peculiar configuration and relation of the corrugations 15 to obtain certain desired results.

An object of the invention is to form and arrange a plurality of corrugations in a metallic plate so as to obtain a desired proportion between strength, rigidity and 20 resiliency.

Another object is to obtain this result with the least amount of raw material and to provide a finished article of the least possible weight consistent with strength requirements.

Another object of the invention is to obtain the desired strength, rigidity and resiliency by forming a metallic plate with integral embossments, each having a wide end 30 and a narrow end and other corrugations or embossments positioned between the narrow ends of adjacent embossments, the wide ends of the embossments being divided by ribs extending toward the middle of the embossments.

35 Another object is to provide such a corrugated metallic plate which can be formed by pressing it (when heated, if necessary) between dies which move toward each other in one direction only.

The construction may be used wherever a strong, resilient panel is desired, but is especially adaptable for railway car structures, such as end walls, side or end doors, hopper 45 doors, floors, roofs, etc., and while I have shown and claimed herein the construction used as an end wall of a railway car, it is my intention to file other applications for patents covering the construction used in other railway car structures.

It is well known that the end walls of railway cars are more likely to be broken or otherwise injured than the side walls. This is due to the inertia thrusts and pressures caused by the shifting of the cargoes

when the train starts or stops. These thrusts may be local, tending to distort the end in some particular spot, as, for example, when a piece of piping or lumber shifts lengthwise imparting a blow against the end wall 60 of the car; or there may be a general tendency to break out the end wall as a whole or tear it away from the framing. For the purpose, therefore, of greater strength and durability, car ends have been constructed 65 of metal plates corrugated or formed with ribs to impart the desired strength, rigidity and resiliency. My construction is especially adaptable to end walls for railway cars (of any type) because it has the strength to 70 resist the continuous pounding of the shifting loads thereon and has the resiliency necessary to absorb these numerous shocks without distortion. Distortion of an end wall might bend the brake mast, thereby causing 75 interference with the operation of the hand brake mechanism. Furthermore, such distortion might reduce the end ladder clearance beyond that prescribed by the Interstate Commerce Commission. When made of 80 several plates secured together the end wall can be made stronger where greater strength is required. A wooden inside lining is required in a railway house car for blocking the lading to and for compliance with the 85 requirements of the Bureau of Explosives of the American Railway Association. Such a wooden lining can be easily applied to my construction.

In the drawings:

Fig. 1 shows the end wall of a railway car with my device applied thereon.

Fig. 2 is a section on line 2—2 of Fig. 1.

Fig. 3 is a section on line 3—3 of Fig. 1.

Fig. 4 is a section on line 4—4 of Fig. 1.

Fig. 5 is a section on line 5—5 of Fig. 1.

Fig. 6 is a detail of a plate reenforced by my arrangement of corrugations.

Fig. 7 is a section on line 7—7 of Fig. 6.

Fig. 8 is a section on line 8—8 of Fig. 6.

Fig. 9 is a section on line 9—9 of Fig. 6.

Fig. 10 is a section on line 10—10 of Fig. 6.

Fig. 11 is a section on line 11—11 of Fig. 6.

The end wall structure comprises a panel composed of one or more metallic plates with my particular embossments formed therein.

In Figs. 1 to 5, inclusive, the embossed plates 1, 2 and 3 extend from top to bottom of the end wall and may be formed with integral flanges 4 along the vertical edges of

the outer plate which overlap and are secured to the side walls 5 of the car by any suitable means. The top edge of the plate is secured beneath the fascia boards 7 and the meeting edges of the plates overlap and are secured together by rows of rivets 8 and the lower edge of the plates are secured to the end sill 9.

Fig. 6 shows a form of the invention applied to a gondola type of car, wherein only one plate is used to form the end panel which extends from side to side of the car and may be provided along the vertical edges with flanges which overlap and are secured to the side walls by any suitable means. The top edge of the plate is secured to the top chord by rivets, while the lower edge is secured by rivets to the end sill.

The plate is provided with embossments or corrugations which have a wide end 20 and a narrow end 21 and a corrugation 22 positioned between the narrow ends of adjacent embossments which extend toward the middle of the embossments and preferably decrease in width and depth from the ends of the embossments. These minor embossments or corrugations 22 have their sides substantially parallel to the sides of the adjacent embossments. The formation of this minor corrugation is such that its inner portion is in the original plane of the plate to provide additional bearing surface for the lining boards. (See Fig. 2.)

Each wide end of the embossments is divided by a rib 23 or corrugation which extends toward the middle of the embossment and preferably decreases in width and depth from the ends of the embossments.

When the embossments are positioned vertically, their maximum depth is located about one-third up from their lower ends, (see Fig. 2) and when the embossments are positioned horizontally their maximum depth is adjacent their middle. (See Fig. 7.)

While the embossments are shown pressed outwardly it is understood that they may be pressed inwardly or partially inwardly and partially outwardly from the original plane of the plate, or the embossments may be placed in any position; for instance, vertically, horizontally or diagonally. The plates may be connected on vertical or horizontal lines and applied to any type of railway car.

The various contours of the corrugations are preferably such that the lengths of the center lines of the metal at every cross section of the corrugated plate normal to the corrugations are equal.

At the plane where the embossments begin to terminate into the original plane of the plate (5-5 in Fig. 1 or 9-9 in Fig. 6) the divided portions 33-33 of the wide end of the embossments; the dividing rib 23 and the space 34 between the adjacent divided portions of adjacent embossments are all equal in width and preferably also equal in

depth so as to form a sinuous configuration of considerable elasticity and resiliency. Such a construction also obtains great strength for the amount of metal used because the neutral plane is midway between the bounding planes of the embossments. At the plane (3-3 in Fig. 1 or 11 in Fig. 6) where the narrow ends of the embossments and the minor corrugations begin to terminate into the plate, these elements are equal in width and spaced apart distances (35) equal to their width, for objects and advantages enumerated above.

The width of the narrow end of the embossment is preferably the same as one of the divided portions of the wide end and also equal to the width of the minor corrugation, so that the contour of the embossed plate at one plane where the embossments begin to merge into the plate is substantially the same as at the corresponding plane at the other end of the embossments.

The maximum pressure and stress on a car end wall is about two feet above the floor and adjacent the middle of the car. The corrugations are a series of parallel beams and when positioned vertically the lower ends of the beams are supported by the under-frame which is the backbone of the car and the upper ends are supported by the end plate. A beam should have its maximum strength adjacent its point of maximum stress, therefore, I prefer to have the strongest part of the individual corrugation, as well as the entire end wall, about two feet from the floor or about one-fourth the length of the corrugation, therefore, the embossments are deeper adjacent this line, the place of maximum depth preferably being where the division of the wide end begins.

In an application for patent Serial No. 133,433, filed September 3, 1926, I have disclosed, and claimed the embossment with relatively wide and narrow ends having the wide ends divided and in still another application for patent Serial No. 133,434, filed September 3, 1926, I have disclosed and claimed a particular arrangement of such embossments.

I claim.

1. A metallic plate formed with a plurality of parallel embossments, each having a wide end and a narrow end, and corrugations positioned between the narrow ends of adjacent embossments extending toward the middle of the embossments, said wide ends being divided by ribs extending toward the middle of the embossments.

2. A metallic plate formed with a plurality of parallel embossments, each having a wide end and a narrow end, and corrugations positioned between the narrow ends of adjacent embossments which decrease in depth and width toward the middle of the embossments, said wide ends being divided by ribs

which decrease in depth and width toward the middle of the embossments.

3. A metallic plate formed with a plurality of parallel embossments, each having a wide 5 end and a narrow end, and corrugations positioned between the narrow ends of adjacent embossments which decrease in depth and width toward the middle of the embossments and having their sides substantially 10 parallel to the sides of the adjacent embossments, said wide ends being divided by ribs extending toward the middle of the embossments.

4. A metallic plate formed with a plurality 15 of parallel embossments, each having a wide end and a narrow end, and corrugations positioned between the narrow ends of adjacent embossments extending toward the middle of the embossments, said wide ends being divided by ribs extending toward the middle 20 of the embossments, said narrow ends and said corrugations being equal in width and spaced apart distances equal to said width.

5. A metallic plate formed with a plurality 25 of parallel embossments, each having a wide end and a narrow end, and corrugations positioned between the narrow ends of adjacent embossments extending toward the middle of the embossments, said wide ends 30 being divided by ribs extending toward the middle of the embossments, said narrow ends and said corrugations being equal in width and spaced apart distances equal to said width, and the divided portions of the said 35 wide ends of adjacent embossments being equal in width and spaced apart distances equal to said width.

6. A metallic plate formed with a plurality 40 of parallel embossments increasing in depth toward their middle, each having a wide end and a narrow end, and corrugations positioned between the narrow ends of adjacent embossments which decrease in depth toward the middle of the embossments, said wide ends 45 being divided by ribs which decrease in depth toward the middle of the embossments, the lengths of the center lines of the metal of every cross section of the embossed plate being equal between the planes where the embossments begin to terminate into the plane of the plate.

7. A metallic plate formed with a plurality 55 of parallel embossments increasing in depth toward their middle, each having a wide end and a narrow end, and corrugations positioned between the narrow ends of adjacent embossments which decrease in depth toward the middle of the embossments, said wide ends being divided by ribs which decrease in depth toward the middle of the embossments, said narrow ends and said corrugations being equal in width and spaced apart distances equal to said width and the divided portions of the said wide ends of 65 adjacent embossments being equal in width

and spaced apart distances equal to said width, the lengths of the center lines of the metal of every cross section of the embossed plate being equal between the planes where the embossments begin to terminate into the 70 plane of the plate.

8. A metallic plate provided with a plurality of embossments, each embossment increasing in width from one end to the other with the wider ends of adjacent embossments 75 being positioned adjacent each other, and corrugations positioned between the narrow ends of adjacent embossments, each of said wider ends being divided by a rib.

9. A metallic plate provided with a plurality of embossments, each embossment gradually increasing in width from one end to the other with the wider ends of adjacent embossments being positioned adjacent each other, and corrugations positioned between 85 the narrow ends of adjacent embossments, each of said wider ends being divided by a rib.

10. A metallic plate provided with a plurality of embossments, each embossment increasing in width from one end to the other with the wider ends of adjacent embossments being positioned adjacent each other, and corrugations positioned between the narrow ends 95 of adjacent embossments, each of said wider ends being divided by a rib, said embossments increasing in depth from each opposite end toward the middle thereof.

11. In combination with the other elements of a railway car, a metallic plate provided 100 with a plurality of embossments, each embossment increasing in width from one end to the other with the wider ends of adjacent embossments being positioned adjacent each other, and corrugations positioned between 105 the narrow ends of adjacent embossments, each of said wider ends being divided by a rib.

12. In combination with the other elements of a railway car, a metallic plate provided 110 with a plurality of embossments, each embossment gradually increasing in width from one end to the other with the wider ends of adjacent embossments being positioned adjacent each other, and corrugations positioned 115 between the narrow ends of adjacent embossments, each of said wider ends being divided by a rib.

13. In combination with the other elements of a railway car, a metallic plate provided 120 with a plurality of embossments, each embossment increasing in width from one end to the other with the wider ends of adjacent embossments being positioned adjacent each other, and corrugations positioned between 125 the narrow ends of adjacent embossments, each of said wider ends being divided by a rib, said embossments increasing in depth from each opposite end toward the middle thereof.

14. A metallic plate provided with a plurality of embossments, each embossment increasing in width from one end to the other with the wider ends of adjacent embossments being positioned adjacent each other, and corrugations positioned between the narrow ends of adjacent embossments, each of said wider ends being divided by a rib, said embossments increasing in depth from each opposite end toward the middle thereof, said embossments, ribs and corrugations so proportioned and dimensioned so as to provide a relatively rigid structure adjacent the middle of the corrugated portion of the plate and a relatively resilient structure adjacent opposite sides of the corrugated portion of the plate.
15. A wall structure for a railway car, com-

prising a metallic plate provided with a plurality of embossments, each embossment increasing in width from one end to the other with the wider ends of adjacent embossments being positioned adjacent each other, and corrugations positioned between the narrow ends of adjacent embossments, each of said wider ends being divided by a rib, said embossments increasing in depth from each opposite end toward the middle thereof, said embossments, ribs and corrugations so proportioned and dimensioned so as to provide a relatively rigid structure adjacent the middle of the wall structure and a relatively resilient structure adjacent the floor and roof of the car.

ARTHUR E. SMALL.
